(57) **CLAIM**

The ornamental design for a dehumidification device for automobile lamps as shown and described.

DESCRIPTION

FIG. 1 is a front, right perspective view of a dehumidification device for automobile lamps, comprised of a main body and a cap, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded perspective view showing the connection between a main body and a cap.

The broken lines and the areas within them in FIGS. 3 and 8 depict portions of the dehumidification device for automobile lamps that form no part of the claimed design. The straight broken line in FIG. 8 depicts the exploded view guide lines that form no part of the claim.

1 Claim, 8 Drawing Sheets
